(57) **CLAIM**

The ornamental design for a cell of a food package tray, as shown and described.

DESCRIPTION

FIG. 1 is a perspective view of a cell of a food package tray, my new design;

FIG. 2 is a top plan view of the cell of a food package tray as shown in FIG. 1;

FIG. 3 is a bottom plan view thereof;

FIG. 4 is a front elevational view thereof;

FIG. 5 is a right end elevational view thereof;

FIG. 6 is a left end elevational view thereof; and,

FIG. 7 is a rear elevational view thereof.

The broken lines are shown for illustrative purposes only and form no part of the claimed design.
